CLAIM

The ornamental design for an image display device, as shown and described.

DESCRIPTION

FIG. 1 is a top, rear, right-side perspective view of an image display device;

FIG. 2 is a front view thereof;

FIG. 3 is a top view thereof;

FIG. 4 is a right-side view thereof;

FIG. 5 is a left-side view thereof;

FIG. 6 is a bottom view thereof; and,

FIG. 7 is a bottom, front, left-side perspective view thereof. The broken lines depict environmental subject matter only and form no part of the claimed design. The dot-dash lines represent a boundary between claimed and unclaimed subject matter. The rear view contains environmental subject matter only, and thus is not depicted. The zig-zag broken lines indicate a portion of the environmental subject matter that has been truncated to allow a clear view of the claimed subject matter.
